BONE SURGERY

John G. Collison, Greensboro, N. C.

Application July 8, 1946, Serial No. 681,934

5 Claims. (Cl. 128—92)

1

The invention relates to bone surgery, and particularly to means for applying an internal fixation plate to a fractured bone.

Internal fixation plates are commonly used in the treatment of certain types of bone fractures, and these plates are connected to the bone fragments by screws which pass through holes in the metal plates and penetrate the adjacent cortex, and sometimes also the distal cortex, depending upon conditions.

In applying a fixation plate to a bone, a number of screws, on each side of the line of fracture, are employed. If any one of these screws is not exactly centered with respect to its hole in the plate, a pressure will be set up in the bone which frequently results in the decay of the bone immediately adjacent such screw. Likewise, if any one of the screws is driven into the bone at such an angle that it will tend to draw on one of the other screws, pressure will be set up with resulting decay of the bone. The degree and extent of the decay depends upon the degree and the extent of the pressure set up in the bone, and it often has very serious results.

In accordance with the present practice the accuracy with which the fixation plate is applied, and hence to a considerable extent the success of the operation, depends upon the personal skill of the surgeon in so applying the screws that no undue pressure will be set up in the bone fragments.

But as is commonly known even the most skillful surgeons are often not skillful in handling and operating mechanical tools. Frequently this is true because the education of the surgeon has not included the mechanical education and experience necessary to the proper handling of mechanical tools, and in other cases it is true because it is common knowledge that some people are so constituted that they simply cannot become skillful in the handling of mechanical tools, regardless of how skillful and brilliant they may be in other arts.

The purpose of the present invention is to so improve the technique of bone surgery in the application of internal fixation plates that the necessity for mechanical skill in the handling of mechanical tools is practically eliminated. In other words, in accordance with the present invention, the technique is such that every one of the screws is necessarily and positively centered with absolute accuracy with respect to its hole in the fixation plate, and every one of the screws, theretofore positively centered, is necessarily driven into the bone perpendicularly to the fixa-

2

tion plate, and thereby entirely avoiding the setting up of undue pressure in the bone.

The invention will be clearly understood from the following description, when taken in connection with the accompanying drawings, in which:

Figure 1 is a perspective view of a fractured bone with the fixation plate partly applied thereto, and showing a guide member about to be applied to one of the holes of the fixation plate and a drill about to be introduced into the guide member;

Figure 2 is a fragmentary elevational view of the guide member applied to one of the holes; parts being broken away and parts being in section;

Figure 3 is a similar view but showing the drill in the guide member and entering the adjacent cortex a slight distance;

Figure 4 is a fragmentary sectional view with the guide member removed and showing the drill after it has been driven entirely through the adjacent cortex;

Figure 5 is a fragmentary sectional view with the previously mentioned parts removed and a screw inserted in an opening of the fixation plate and having a pilot point fitting neatly in the previously drilled hole in the cortex;

Figure 6 is a similar view but showing the screw as having been driven part way into the cortex;

Figure 7 is a similar view but showing the screw driven all the way in so that the cruciate head is seated in the opening of the fixation plate;

Figure 8 is a horizontal sectional view of the drill, taken on line 8—8 of Figure 1; and

Figure 9 is an end view of the screw.

Referring to the drawings in more detail, numeral 1 indicates a bone which has been fractured at 2 and reset ready for the application of a fixation plate 3. The plate is preferably curved slightly so that its edges rest on the bone, thereby preventing any tendency of the plate to rock.

The plate is provided with any desired number 45 of holes 4 to receive the screws by which the plate is fixed to the bone fragments on both sides of the fracture. In the specific embodiment illustrated, each of the holes has a tapered upper portion 5 leading to a cylindrical lower portion 6, though of course these openings could be of various shapes.

Numerical 7 refers to a centering guide member which has a central cylindrical bore 8 extending throughout its length, and which has 55 adjacent its lower end a tapered portion 9 lead-

ing to a cylindrical portion 10; the portions 9 and 10 being of such size and shape as to make a neat fit with the previously described portions 5 and 6, respectively, of the openings in the fixation plate.

When the bone has been reset and the fixation plate is in place ready to be secured to the bone fragments, the first step is to place a centering guide in one of the openings in the plate. By reason of the parts 9 and 10 of the guide cooperating with the parts 5 and 6 of the opening, the guide will make an exact fit in the opening and will extend from the fixation plate exactly perpendicular thereto, and with the central bore 8 of the guide exactly centered with respect to the opening or hole 4.

The next step is to introduce a drill 11 into the central bore 8 of the centering guide, as suggested in Figure 1 and as shown in Figure 3. Also as shown in Figure 3 the diameter of the drill is substantially the same as the diameter of the central bore 8 of the guide, so that the drill makes a neat sliding and rotating fit with the guide. Thus by reason of the guide being centered with respect to the hole 4 of the fixation plate, and the drill being centered with respect to the guide, the pin point 12 of the drill contacts with the bone at a point which is necessarily exactly centered with respect to the hole 4.

The drill is now turned to cause it to enter the bone only a very slight distance, so that its centered position is fixed, and the centering guide is then removed, leaving the parts as shown in Figure 3 but with the guide removed from that figure.

The next step is to drill the hole through the adjacent cortex and also through the distal cortex if the conditions are such that it seems necessary to do so. For the purpose of illustration the hole is drilled through only the adjacent wall of the cortex, as shown in Figure 4. In drilling this hole it is of great importance that the wall of the hole be perfectly cylindrical throughout its length and that its direction be exactly perpendicular to the fixation plate. In this drilling operation, particularly when the surgeon may not be very skilled in the handling and operation of mechanical tools, there is likely to be some wobbling of the drill with the result that the entering end of the hole will become enlarged and irregular, and the direction of the drill may change. To prevent these most undesirable results, it will be noted from Figures 3, 4, and particularly 8, that the drill flutes do not have any relief. Drills are commonly provided with flute relief, and hence when wobbling of the drill occurs the opening is enlarged and made irregular, but with the drill disclosed herein, without flute relief, the flute surface is cylindrical, and even when there is considerable wobbling of the drill the hole bored will remain cylindrical throughout its extent, as shown in Figures 4 and 5. And as the drill necessarily entered the bone exactly perpendicular to the plate, it must necessarily follow that course throughout.

One of the holes having been drilled through the cortex in the manner described above, the drill is withdrawn and the next step is to insert one of the screws for attaching the fixation plate. The novel construction of the screw, and the method of its application, are illustrated in Figures 5, 6, 7 and 9.

Each of these screws has a cruciate head and a threaded cylindrical body 13, in advance of

which is a very short tapered threaded portion 14 and the end of the screw, in advance of the tapered threaded portion, is a cylindrical pilot portion 15. In the drawings this pilot portion is shown as unthreaded, but in actual practice it would have very shallow threads, because the drilled hole in the bone is of slightly greater diameter than the root diameter of the screw 13, so that when the thread 13 enters the bone the bone will not reach down to the bottom of the threads which would cause fragments of the bone to break off at the sharp edge of the bone thread. Hence, as the diameter of the drilled hole is slightly greater than the root diameter of the thread, there will remain a very shallow thread on the pilot portion which fits snugly in the drilled hole in the bone.

This pilot portion 15 has oppositely disposed longitudinally extending recesses or pockets 16. These recesses extend from the end of the screw through the tapered portion 14 and through one or more of the threads 13 on the body. These recesses or pockets, where they pass through the tapered portion 14, produce a self-tapping screw, and to improve the self-tapping effect the threads on the tapered portion 14 have a ground relief, as indicated by numeral 17 in Figure 9, so that the screw will enter the bone more easily. The recesses or pockets 16 additionally provide relief for the bone chips by collecting them therein.

By reference to Figure 5 it will be noted that the cylindrical pilot portion 15 of the screw has substantially the same diameter as that of the hole which has been drilled in the cortex, so that the pilot portion will make a snug fit in this hole, and hence the screw itself will be positively held in perfect alignment and perfectly centered with the drilled hole, and thus the screw will enter and follow the exact course of the hole, which is perpendicular to the fixation plate.

The various steps described hereinbefore in connection with the first screw are repeated in exactly the same manner with all of the other screws, and as previously mentioned, the screws may go through only the adjacent cortex, as illustrated, or they may also go through the distal cortex, depending upon conditions, and in either case the technique and the apparatus remain the same, except of course longer screws are used when they are to extend through both cortices.

From the foregoing description it will be apparent that without any mechanical skill on the part of the surgeon in the handling of mechanical tools, the drill is exactly and positively centered with respect to the hole in the fixation plate, that the drill necessarily enters the bone exactly perpendicular to the fixation plate, and that even with very considerable wobbling of the drill during the drilling operation the resulting hole will be perfectly cylindrical throughout its length and will be perpendicular to the fixation plate throughout its length, by reason of the fact that the flute surfaces being without flute relief are cylindrical, that the drilled hole in the bone and the hole in the fixation plate are perfectly centered because the screw has a cylindrical pilot portion which has a snug fit in the drilled hole and the tapered screw head makes a snug fit with the tapered portion 5 of the hole in the fixation plate.

By reason of the fact that each of the screws is exactly centered with respect to each hole of the fixation plate and the fact that each screw is perpendicular to the fixation plate, it follows

that no undue pressure is set up in the bone, which pressures often cause bone decay resulting in unsuccessful operations.

Having fully described the invention, what I claim is:

1. In bone surgery, a surgical bone screw, said screw having a threaded portion and a cylindrical pilot portion, said cylindrical pilot portion adapted to fit snugly in a hole drilled in the bone cortex, and one or more recesses or pockets provided in said screw and extending from a point in the pilot portion to a point in the threaded portion to provide a self-tapping screw and to receive the bone chips.

2. In bone surgery, a surgical bone screw, said screw having a threaded portion and a cylindrical pilot portion, said cylindrical pilot portion adapted to fit snugly in a hole drilled in the bone cortex, one or more recesses or pockets provided in said screw and extending from a point in the pilot portion to a point in the threaded portion to provide a self-tapping screw and to receive the bone chips, and the threads of the self-tapping section having ground relief.

3. In bone surgery, a surgical bone screw, said screw made of metal suitable for bone surgery, a cruciate head on said screw, said screw comprising a threaded portion and a cylindrical pilot portion, said pilot portion adapted to fit snugly in a cylindrical hole drilled in the bone cortex, and one or more recesses or pockets provided in the screw and extending from a point in the pilot portion to a point in the threaded portion to provide a self-tapping screw and to receive the bone chips.

4. In bone surgery the method of applying a fixation plate to the fragments of a fractured bone comprising the steps of drilling a cylindrical hole

through the bone cortex centered with respect to a hole in the fixation plate and perpendicular to the fixation plate, and then causing a leading cylindrical portion of a surgical screw to enter the drilled cylindrical hole in the cortex in a position perpendicular to the fixation plate and then driving the screw home.

5. In bone surgery the method of applying a fixation plate to the fragments of a fractured bone comprising the steps of employing a centering guide to start the drilling of a cylindrical hole through the bone cortex centered with respect to a hole in the fixation plate and perpendicular to the fixation plate, then removing the centering guide, then completing the drilling of the cylindrical hole through the bone cortex, and then entering with a neat fit a leading cylindrical portion of a surgical screw in the drilled cylindrical hole in the cortex in a position perpendicular to the fixation plate and then driving the screw home.
